UNITED STATES PATENT OFFICE.

JAMES FERRIER, OF WOWAN, AUSTRALIA.

COTTON PICKER.

Application filed June 30, 1926, Serial No. 119,647, and in Australia July 16, 1925.

My improved rotor or rotors for a handpiece of a cotton picking apparatus, embodies rock bars which carry pickers, the handpiece having a mouth which can be brought adjacent to cotton bolls in the field, the boll being drawn by inwardly moving air towards the mouth, and the cotton being plucked from the boll by the pickers, and then drawn into the handpiece and in due course released for conveyance where desired.

One object of this invention is to provide rock bars within a casing which has openings through which the picker points may project variably so as to effectively detach, then convey, and thereafter release the cotton.

In the drawings herewith, which are in some cases diagrammatic, I illustrate rotors according to this invention, and show several forms of the casings and other elements of the rotors, but other modifications are obviously usable, and the designs and numbers of the parts used may be varied while retaining matter hereinafter claimed.

Figure 1 is a side elevation of a rotor viewed in the direction of the arrow in Figure 2, partly in section on line F¹ of Figure 2, the rotor having rows of slots, slots of successive rows being in alignment circumferentially, one slot being provided for each picker. There is also illustrated at one end of the rotor a nonrotating casing and other parts of the handpiece head.

Figure 2 is mainly a transverse sectional view of the rotor of Figure 1, but shows also part of an end disc.

Figure 3 is an end sectional view on line F³ of Figure 1, omitting head parts outwardly of the cam cover.

Figure 4 is a perspective view of a picker. Figures 5 to 9 illustrate modifications.

Figure 5 is a side sectional view of part of a sheet metal rotor casing and a rock bar.

Figure 6 is a sectional perspective view of parts in Figure 5.

Figure 7 represents part of a rotor casing having rows of slots which are relatively staggered circumferentially.

Figure 8 is a perspective view of part of a rotor having a ridged casing.

Figures 9 and 10 are end sectional views of parts of rotors having modified ridged casings, the ridging being variable to suit the number of the rock bars.

1 is a rotor shaft supported in bearings in the handpiece head H, part of which is indicated by way of example. The head will

vary in form in practice, and will have one, two, or more rotors. The mouth of the head is indicated at M. Shaft 1 carries means shown as discs 2 which support the rotor casing 3, shown cylindrical in Figures 1 to 3, but of ridged section in Figures 8 to 10, there being longitudinal depressions or corrugations 5 between ridges 4, having curved surfaces 6 which assist to repel boll husks. Longitudinal partitions 7, which are spaced apart within the rotor casing 3 and which might be employed to support the same, are usable to reduce air movement within the rotor, and extend from end to end of the casing; in Figure 2 they radiate from a central boss 7^a, and each enters an anchoring groove in the casing.

In Figure 9 the partitions are integral with boss 7^a. The peripheries of discs 2 either project as at 2^a in Figures 7, 9 and 10, or as in Figures 1 and 2 have substantially the diameter of the rotor casing. Each disc edge is protected as by being located within a guard rim R on the handpiece head, this construction preventing cotton fouling shaft 1 or its bearings.

The rock bars 10 are spaced around shaft 1, each carrying any desired number of pickers 11 of suitable type, six rock bars being shown in Figures 2 and 3, although in practice any other appropriate number is usable, each being restrained from displacement longitudinally by any suitable means, as washers 3^a for example.

The picker openings in the rotor casing are in the form of longitudinal sets or rows of slots 12 through which the tips of the pickers will project more or less at intervals during cotton picking, the rock bars oscillating to cause the pickers to rise, or erect themselves into position to project outwardly to pick cotton and to become, during the rotation of the casing, lowered, reclined, or retracted, so as to leave the cotton free at a suitable location.

The picker motions occur in suitable circumferential positions of the pickers, which are not necessarily retracted right into the casing.

Rock bar oscillation causes the pickers to swing; at the same time the rotor revolves. I illustrate in Figure 4 one form of picker formed of a single spring wire or bristle having a tip 11^a which is somewhat bent, that is to say, is hook like, but the tip is also effective if straight.

These pickers also have means to loosely embrace their support shown as rock bar 10, and to increase the resilience of the picker. Thus 11^b is a coil. Each picker has a stub 5 or shank 11^c of suitable form for anchorage of the picker in a rock bar hole or recess—see Figures 4 and 5. The variations in the forms of pickers which are usable are considerable.

10 To rock each bar 10 any suitable mechanism is used, and I show at one end of each rock bar a crank 15, see Figures 1 and 3, although mechanical equivalents of cranks, such as eccentrics, are usable. Each crank 15 engages a cam track 16 in a stationary member shown as a cover 17 attached to the hand-piece head H. The cranks are urged by springs 18 against the cam surface so that each rock bar is thus set in its proper position, and the pickers carried thereby are properly positioned relatively to the rotor face. As shown in Figure 3 there are means to prevent free movement of the cranked ends after they are withdrawn from the cam; 25 these means are shown as stops 19. As shown in Figure 3 a leading-in cam ramp 20 enables cranks 15 to be set into working position, the rotor or casing being turned during assembly, causing the successive 30 cranks to mount the cam track 16 and become located as illustrated. A cam of ridge or groove nature is suitable; if a groove is used the springs 18 are unnecessary.

The previously-mentioned slots 12 of successive rows are abreast in Figure 1, that being preferable when a rotor carries numerous pickers. The slots in Figure 7 are staggered circumferentially, but with such slots either set abreast or staggered the rotor 40 outer surface is longitudinally or circumferentially ridged or domed at will.

A slot can be so elongated as to accommodate pickers of more than one row.

It is also obvious that when the picker tips 45 project, they will engage the cotton of any adjacent boll, and detach it from its husk, and that when they recede they will free the cotton. To assist the picker action when freeing cotton, the slots have suitable ramp-like edges or lips which are indicated at 13, Figure 6. The slot walls diverge inwardly 50 at 14, Figure 8, but as an equivalent the lips could project inside the casing. The outer lips 13 also keep out the husks, and the extra clearance space provided by the diverging faces of walls 14 promotes picker action 55 free from undue friction on the slot faces, allowing the pickers to swing correctly even if displaced somewhat from normal positions.

By having slot lips which are ramp-like, an undulating surface is provided circumferentially of the rotor, and this is useful during its revolution. But a similar undu-

lation is obtained by fluting or corrugating 65 the rotor surface, an example being shown at 13^a, Figure 8.

I claim:—

1. In a cotton picker, a head; a rotor mounted therein and embodying a casing 70 provided with a plurality of sets of slots; driving means for the rotor; a plurality of rock bars, one for each set of slots, mounted within the rotor casing to move bodily with the same; a set of pickers carried by each bar 75 opposite the respective set of slots, each picker having at one end a tip adapted to move outward and inward through the adjacent slot and intermediate its ends a coil which embraces the associated bar, the other end of the picker being anchored to said bar; a stationary cam within the head; and a crank on each bar engaging said cam to impart an intermittent oscillation to the bar during its bodily movement with the rotor 85 but independent of such bodily movement, thereby to effect the operation of the pickers.

2. In a cotton picker, a head; a rotor mounted therein and embodying a casing provided with picker openings; driving means 90 for the rotor; a plurality of rock bars mounted within the rotor casing to move bodily with the same; a set of pickers carried by each bar opposite the picker openings, each picker having at one end a tip adapted to move outward through the adjacent opening to pick cotton from a boll and then rearward through said opening to withdraw from the picked cotton, the other end of the picker being anchored to the associated bar and its intermediate portion being formed as a coil which embraces said bar; a stationary cam within the head; and a crank on each bar engaging said cam to impart an intermittent oscillation to the bar during its bodily movement with the rotor but independent of such bodily movement, thereby to effect the operation 100 of the pickers.

3. A cotton picker, according to claim 2, in which the rotor comprises a body portion 110 whereon the rotor casing is supported, such body consisting of a central hub and a plurality of longitudinal partitions connected thereto, adjacent partitions defining an individual chamber for each rock bar and the 115 pickers carried thereby.

4. A cotton picker, according to claim 1, in which the stationary cam consists of a track having an entrance ramp; and in which each crank has a spring associated with it for 120 pressing it against the cam track, stops being provided for preventing free movement of the cranks on being withdrawn from engagement with said track.

In witness whereof I have hereunto set my 125 hand.

JAMES FERRIER.
